Inventor:

J. Hartman Jr.

UNITED STATES PATENT OFFICE.

JOHN HARTMAN, JR., OF PHILADELPHIA, PENNSYLVANIA.

IMPROVEMENT IN CRUTCHES.

Specification forming part of Letters Patent No. 42,473, dated April 26, 1863; antedated December 22, 1863.

To all whom it may concern:

Be it known that I, JOHN HARTMAN, Jr., of the city and county of Philadelphia, and State of Pennsylvania, have invented a new and useful Improvement in Crutches; and I do hereby declare that the following is a full, clear, and exact description of the construction and operation of the same, reference being had to the annexed drawings, making a part of this specification, in which—

Figure 1 is a perspective view of an improved armpit-rest. Fig. 2 is a vertical section of the same. Fig. 3 is a perspective view of a gutta-percha tube, A, which constitutes the support for the armpit. Fig. 4 is a perspective view of one of the jaws B.

Like letters in all the figures represent the same parts.

The nature of my invention consists in combining a tube of gutta-percha, or an equivalent substance, with the staff or frame of the crutch in such a manner as to form a yielding and easy rest for the armpit.

To enable others skilled in the art to make and use my invention, I will proceed to describe its construction and operation.

A is a tube, which I make of gutta-percha, or other equivalent substance.

B B are metallic jaws, between which the said tube is secured by means of the screws C C. The said screws are of conical form, as represented in the drawings, (see Fig. 2,) and there are conical openings a a in the jaws B B, in which the ends of the tube are expanded by the force of the said screws. By this arrangement the tube is securely held in its

place; but in order to fasten the ends of the tube more perfectly I construct the screws C C with annular grooves b b, into which the former contract when forced into their sockets, as represented in Fig. 2. The jaws B B have openings d d, into which the prongs of the frame of the crutch are inserted.

There may be a cross-rod combined with the jaws B B in any convenient manner to add stiffness to them, if desired, or the jaws may be made in a single piece. It will readily be seen that the tube A will yield to the pressure exerted upon it by the weight of the body sufficiently to accommodate itself to the form of the armpit, and thus give an easy support to the latter.

Having thus fully described the construction and operation of my improvement in crutches, what I claim therein as new, and desire to secure by Letters Patent, is—

1. Constructing and combining with the staff or frame of the crutch a tube of gutta-percha, or other equivalent substance, to form a yielding and easy rest for the armpit, substantially as described.

2. The combination of the tube A with the jaws B B by means of the conical screws C C, or their equivalent, substantially in the manner and for the purpose above set forth.

In testimony that the above is my invention I have hereunto set my hand and affixed my seal this 16th day of November, 1863.

J. HARTMAN, JR. [L. S.]
